UNITED STATES PATENT OFFICE.

ABEL R. MULDER, OF ROCHESTER, NEW YORK.

BREAD-CUTTING MACHINE.

1,289,516.

Specification of Letters Patent. Patented Dec. 31, 1918.

Application filed November 30, 1917. Serial No. 204,724.

To all whom it may concern:

Be it known that I, ABEL R. MULDER, a subject of the Queen of Holland, residing at Rochester, in the county of Monroe and State of New York, have invented certain new and useful Improvements in Bread-Cutting Machines, of which the following is a specification.

This invention relates to bread cutters and has for its object to provide an automatic machine provided with a continuously revolving knife in which the bread is fed forward a uniform distance for each revolution of the knife so that it will be cut in slices of uniform thickness.

Means are also provided by which the thickness of the slices cut may be varied at will by an adjustment provided therefor.

These and other objects of the invention will be fully illustrated in the drawings, described in the specification and pointed out in the claims at the end thereof.

In the drawings,

Figure 1 is a side elevation of the machine, the hood guarding the cutting knife being partly broken away.

Fig. 2 is a vertical section on the line 2X—2X of Fig. 1.

Fig. 3 is a vertical section on the line 3X—3X of Fig. 1.

Fig. 4 is a vertical section on the line 4X—4X of Fig. 1.

Fig. 5 is a vertical section on the line 5X—5X of Fig. 3.

Fig. 6 is a vertical section on the line 6X—6X of Fig. 5.

Fig. 7 is a vertical section on the line 7X—7X of Fig. 5.

Fig. 8 is a perspective view of the guard for guarding the rotary knife.

In the accompanying drawings like reference numerals indicate like parts.

In the drawings, reference numerals 1 and 2 indicate the uprights which support the machine. These uprights are fastened at the bottom to a base 3 which is made preferably of wood, the ends of which are reinforced by the bars 4 and 5 mortised into the base in which are threaded the stud bolts

6, 6 which pass through the feet on the bottom of the legs of the uprights. Each of the uprights is formed with an opening 7, 7. The uprights are connected together by the channel 8 which is fastened to each of the uprights, the bottom of the channel being fastened to the uprights at the bottom of the openings 7, 7. The side 9A of the chan-

nel is also fastened to the upright at the side of the opening as indicated by the screws 9, 9 and 10, 10. The uprights support the channel 8 and the channel in turn supports the loaf of bread while being fed forward to the cutting knife.

Mounted in the top of the uprights is the shaft 11 provided with a hand wheel 12 on one end thereof, the wheel being equipped with a handle 13 by which it may be turned and with it the shaft 11. On the opposite end of the shaft 11 is the cutting knife 14 provided with a boss 15 which engages the shaft 11 and is provided with the set screw 16 by which it is clamped thereon. The knife 14 has a curved cutting edge which is substantially that of an involute curve of a circle and is intended to make a shear cut as it rotates. The back of the knife is cut away at an angle which when the knife is in the position shown in Fig. 2, substantially coincides with the side and top of the opening 7. As soon as the cutting operation is finished, the opening is fully uncovered by the knife permitting the bread to feed forward freely immediately thereafter and the feeding mechanism is timed so that the feed takes place after this opening is fully uncovered and is completed before the knife begins the next cut. The knife is guarded by the housing 17 which has the two guides 18, 18 thereon which engage with the flanges 19, 19 on the upright 1 by which it is held in place. The guard is cut away on the inner side so as to inclose and rest on the horizontal flange 20 and the vertical flanges 21 and 22 that project inwardly from the uprights by which it is held in place.

Fastened on the shaft 11 adjacent to the handwheel 12 is the cam 23 which revolves with said shaft. Mounted on the upright 2 or the pivot screw 24 is the rocking lever or walking beam 25 which at its inner end carries an antifriction roller 26 which makes engagement with the cam 23 and by which it is oscillated. The lever is slotted as shown at 27 and in this slot is provided a stud 28 which is mounted to slide therein and is clamped in any position that is desired by the wing nut 29. To the end of this stud is fastened one end of the chain 30. The other end of the chain is fastened to the drum 31 at 32. As the lever 25 rocks up and down the chain is pulled and the drum is rotated in one direction by the unwinding of the chain which is always tangential to the drum by which a uniform pull at all angles

of the lever is secured. The drum is rotated in the opposite direction by the spiral spring 33, one end of which is fastened to the inside of the drum and the other end of which is fastened to a fixed stud 24. The torsion of the spring rotates the drum in the opposite direction and winds up the chain, pulling down on the lever 25 and keeping the anti-friction roller 26 in close engagement with the cam 23. On the drum is provided a plate 35 on which is carried two spring pressed pawls 36 which pawls engage with the ratchet wheel 37 by which pawls the oscillation of the drum in the direction that it is rotated by the chain 30 is communicated to the ratchet wheel. By this arrangement the ratchet wheel is fed forward by a step by step movement which varies with the distance by which the stud 28 is set from the center of rotation 24. The ratchet wheel 37 is integral with the gear 38 which gear in turn meshes with the pinion 39 which is integral with the feed screw 40. By this mechanism the feed screw is turned through a substantially definite angle on each revolution of the cutting shaft and the cam 23 is shaped so that this feed takes place in about 120° of rotation of the shaft 11 and the cam is set so that it starts when the knife 30 is in the position shown in Fig. 2.

This movement of the feed screw is utilized to feed the bread forward to the cutter by mechanism that I will now describe.

Mounted to travel along the channel 8 is the carriage 41, which carriage is provided with a handle 42. At the base of the handle where it joins the carriage is formed the opening 43 which encircles the feed screw 40. Pivotedly mounted on the handle is the pawl 44 which engages with the groove in the screw. The spring 45 is provided by which it is held in this position. By reason of the engagement of the pawl as the screw turns, the carriage is fed toward the knife, and this movement will continue as long as may be desired and when it is desired to introduce another loaf of bread, the pawl may be rocked by squeezing the handle and compressing the spring 45 after which the carriage may be slid back to a new position where the pawl will again engage the screw and the forward feed of the carriage will again be secured thereby. The carriage is provided with a vertical guide 46 on which slides the jaw 47 which has teeth on the under side thereof projecting downwardly, similar teeth being provided in the carriage projecting upwardly. The carriage forms the lower jaw which co-operates with the upper jaw to clamp the loaf of bread between them for the purpose of feeding. The upper jaw is drawn down on the loaf by the spring 48.

Outside of the frame 1 is provided a trough 50 pivotally mounted at 51 which catches the pieces of bread as they fall from the knife. The trough is channel shaped and the bottom of it is slightly lower than the channel 8.

The operation of the machine is as follows:

The knife may be placed across the opening in the upright 1. The loaf of bread is then placed on the channel 8 with its end against the knife. The carriage is then brought forward into engagement with the rear end of the loaf of bread and the upper jaw is closed down on it forcing the end of the loaf into engagement with the lower jaw. The carriage is then engaged with the feed screw and the handwheel is then rotated causing the loaf to be fed to the knife and cut in slices.

I claim:

1. In a bread cutter, the combination of a frame having a base, a traveling carriage, a feed screw for advancing said carriage, means for turning said screw intermittently through a fixed angle, said means comprising a drum, a chain attached to and partially wound on said drum at one end, a rocking lever to which the other end of said chain is attached, means for intermittently rocking said lever,

2. In a bread cutter, the combination of a frame having a base, a traveling carriage, a feed screw for advancing said carriage, means for turning said screw intermittently through a fixed angle, said means comprising a drum, a chain attached to and partially wound on said drum at one end, a rocking lever to which the other end of said chain is attached, means for intermittently rocking said lever in one direction, a spring on said drum for rocking said lever in the other direction, said means for turning said screw being adapted to rotate said screw in one direction by the oscillations of the drum.

3. In a bread cutter, the combination of a frame having a base, a traveling carriage, a feed screw for advancing said carriage, a ratchet wheel on the end of said feed screw, a drum mounted to rotate on said feed screw, a spring pressed pawl mounted on said drum and engaging said ratchet wheel, a chain attached to and partially wound on said drum at one end, a rocking lever to which the other end of said chain is attached, means for intermittently rocking said lever in one direction, a spring on said drum for rocking said lever in the other direction, said pawl being adapted to intermittently turn said feed screw in one direction on the oscillation of said drum by said chain.

In testimony whereof I affix my signature.

ABEL R. MULDER.
